UNITED STATES PATENT OFFICE.

MILON JAMES TRUMBLE, OF LOS ANGELES, CALIFORNIA, ASSIGNOR TO TRUMBLE
REFINING COMPANY, A CORPORATION OF ARIZONA.

PROCESS OF REFINING PETROLEUM OR SIMILAR OILS AND APPARATUS FOR CARRYING ON THIS PROCESS.

1,070,361.

Specification of Letters Patent. Patented Aug. 12, 1913.

Application filed January 14, 1913. Serial No. 742,063.

To all whom it may concern:

Be it known that I, MILON JAMES TRUMBLE, a citizen of the United States, residing at Los Angeles, in the county of 5 Los Angeles and State of California, have invented a new and useful Process of Refining Petroleum or Similar Oils and Apparatus for Carrying on this Process, of which the following is a specification.

10 Natural petroleum oils as produced from the ground are composed of an indefinite number of series of oils, each of such series being of a different combination of hydrogen and carbon and susceptible of volatilization at its own particular temperature.

In the ordinary means for partially vaporizing crude petroleum oils heretofore in practical use, it has been difficult to expand the several series desired and maintain 20 throughout the evaporating chamber a uniformity of temperature by which the vapors thus expanded are held in their proper expanded condition until the same are withdrawn from the evaporating chamber with- 25 out some of the series thus expanded being subjected to a lower temperature than that at which they originally expanded or to a lower temperature at which some of the vapors will condense. When such series are 30 subjected to the least decrease in temperature within the still below that at which they expanded, they condense and fall back into the oil or onto a heated surface where they are again suddenly expanded. The 35 sudden expansion of such condensed oil, in most instances, causes a disruption of the union of hydrogen and carbon going to make that series and produces what is commonly termed a "cracking" or liberation of 40 "marsh gas" or other light gases and consequent deposit of partially freed carbon. The "marsh gas" thus generated is a non-condensable gas and is a total loss in so far as refined products from the oil are con- 45 cerned, while the partially freed carbons remaining in the oil, or when carried into the distilled products, are a detriment to the quality of the finally finished products. When such partially freed carbons are car- 50 ried over with the vapors into the finished gasolines, benzins or kerosenes they cause a discoloration of such oils when they are subjected to the actinic rays of light, and hence it is necessary that such products be treated

with acid in order to break down and precipitate such carbons into that which is commonly called "sludge" by the refiner.

I have discovered that natural hydrocarbons existing as petroleum oils may be vaporized within an evaporating still and be carried out of such still without any of the different series of the oils condensing within the still, thereby preventing cracking of any of the oils being treated. In order to accomplish this end I have discovered that it is necessary to provide an evaporating chamber wherein the vapors may be freed from a previously heated body of oil which is continuously fed thereto and in which the oil is divided to decrease the tension of the oil upon the vaporizable series of oils, and to obstruct and retard the passage of the divided oil and to maintain such oil in uniformly divided condition during its passage through the chamber, and to provide means to prevent radiation of heat from such chamber, thereby preventing a decrease of temperature within the chamber, and provide auxiliary heating means whereby the temperature within such evaporating chamber can be regulated to maintain the same at a parity with the temperature of the incoming oils to the chamber or to increase the temperature of such chamber, if desired, to a point above that of the temperature of the incoming oils, whereby the vapors expanded and liberated from the oil remain until removed from the still or evaporating chamber at or above the temperature at which they were originally liberated from the oil.

I have found that a desirable form of evaporating chamber for the purposes above described exists in the improvement in evaporators for petroleum oils or other liquids invented by me for which Letters Patent of the United States was granted July 4th, 1911, No. 996,736, but other forms of evaporating or expanding chambers will suggest themselves to those skilled in the art of oil refining after having familiarized themselves with my present invention.

One very important object of my invention is to provide an improved process of evaporating petroleum, as hereinafter more particularly set forth.

The principal object of my invention is to provide a new process whereby petroleum

or similar oils may be economically refined without disturbing the various series of hydrocarbons that go to make up such oils.

Another object of my invention is to provide a cheap and simple apparatus which will effectually heat an oil to the point at which all of the series desired to be distilled therefrom will volatilize, and provide an evaporating chamber arranged adjacent to such heating apparatus to receive the oil, divide the oil to relieve the tension thereof upon the several series contained therein which are expanded to the point of vaporization, retard the oil in its passage therethrough to permit sufficient time for the entangled vapors to free themselves from the unvaporized liquid, and to provide means for preventing heat radiation from such chamber and maintaining the temperature of such evaporating chamber at a parity with that of the expanded series, whereby such expanded series will be maintained in their expanded or volatilized condition until they are withdrawn from the evaporating chamber.

Another object of my invention is to provide a simple, cheap and convenient apparatus for the purposes described which will practically conserve the heat applied through the furnace.

Other objects and advantages will be apparent from the following specification, and particularly pointed out in the claims.

My invention comprises first, the process of treating hydrocarbon oils in which the body of oil is first heated to a temperature sufficiently high to volatilize all of the several series thereof which it is desired to remove from the oil and under sufficient pressure to maintain it in liquid form, in introducing such heated oil into a chamber, dividing the oil and while maintaining such divided condition retarding the passage through such chamber to permit complete expansion and vaporization of the molecules of the selected series, maintaining both oil and vapors at the temperature of the oil when introduced into the chamber, preferably by introducing into the chamber a heated gaseous medium, such as superheated steam, which is above the temperature of the incoming oil, withdrawing the vapors from the presence of the oil, and then condensing the same.

My invention also consists in providing in combination with an evaporating or expanding chamber constructed and arranged to suitably retard or obstruct the passage of the oil therethrough and having a vapor outlet and residuum outlet for hydrocarbon oils, means for heating a flowing body of oil, means connecting such oil heating means with the evaporating chamber and insulating means surrounding such chamber whereby the temperature within the whole of the

evaporating chamber is maintained at a parity with the temperature of the heated oil from the heater, whereby condensation of vapors of oil are prevented within the chamber.

My invention also includes in combination, an evaporating chamber constructed to retard the flow of oil therethrough and maintain the oil in a suitably divided condition, and having a vapor outlet and a residuum outlet for petroleum oils, means for heating a flowing body of oil, means connecting such oil heating means with the evaporating chamber, heat insulating means arranged around such evaporating chamber for maintaining the temperature within the evaporating chamber on a parity with the temperature of the heated oil, and means for dividing the oil within the evaporating chamber to release the tension upon the expandible series therein at the temperature of the evaporating chamber and oil.

My invention also comprises the combination of a furnace, means for heating a continuous flow of petroleum oil arranged within the furnace, a vertical evaporating chamber arranged adjacent to the furnace, a conduit arranged to convey the heated oil from the heating means in the furnace to the top of the evaporating chamber and deliver the same thereto to permit such liquid to pass by gravity therethrough, said chamber being constructed to retard the flow of oil therethrough and maintain the oil in a suitably divided condition: such evaporating chamber being insulated against heat radiation and provided with superheated steam inlet means thereto, whereby the temperature of the heated liquid introduced into the chamber is maintained during its passage through the chamber and the evolved vapors therefrom are maintained at the temperature at which they are evolved, such evaporating chamber being provided with vapor outlet means and residuum outlet means.

My invention also consists in the combination of furnace having a flue communicating therewith, a liquid heating coil arranged within the furnace, and a vertical evaporating chamber having a vapor outlet and residuum outlet, located in the furnace flue, means for conducting a liquid from the heating coil within the furnace into the top of the evaporating chamber to deliver a heated liquid thereto to pass downwardly through such evaporating chamber, said chamber being constructed to retard the flow of oil therethrough and maintain the oil in a suitably divided condition and insulating means surrounding the lower part of the evaporating chamber.

My invention further consists in providing a uniformly heated evaporating chamber which is insulated against heat radiation, oil inlet means for introducing a heat-

ed oil into the top of such evaporating chamber, means for dividing such oil arranged below the oil inlet to reduce the tension on the expanded liquid and thereby assist the expanding action of heat to liberate vapors therefrom, means for introducing superheated steam into the bottom of the insulated evaporating chamber, whereby the expanded or vaporized portions of the oil are maintained in a buoyant condition and prevented from coming into contact with a colder temperature while within the evaporator, vapor outlet means for conducting the vapors from the chamber, and residuum outlet means for conducting residuum from the bottom of the chamber.

The accompanying drawings illustrate a preferred form of my invention.

Figure 1 is a perspective view of an apparatus embodying my invention. Fig. 2 is a vertical section of the apparatus on line x^2-x^2 Fig. 1. Fig. 3 is a front elevation of the furnace and oil heating coil. Fig. 4 is a longitudinal, vertical section of the furnace showing one retort. Fig. 5 is a horizontal, sectional plan, on reduced scale, showing the arrangement of the furnace and one form of the heat insulating means around the evaporating chamber, such evaporating chamber being shown in its preferred relation with the furnace.

I provide a furnace 1 having a liquid heating coil 2 arranged therein, such heating coil preferably consisting of a plurality of sections of tubular retorts such as 3, 3, 3, 3, 3 lying parallel with each other within the furnace and connected together at their ends to form a continuous coil. The petroleum oil to be heated is admitted at 4 and passes through each of the several retorts 3, and when raised to the temperature desired is conveyed from the last retort of the coil through an insulated pipe 5 to the top of the evaporating chamber.

45 The furnace body as shown is subdivided by walls 6 and 7 to form three compartments 8, 9 and 10, and two retorts are arranged within each of these compartments. Openings *a*, *b* and *c* are provided in the front wall of the furnace for the introduction of fuel to heat the retorts. The rear portion of walls 6 and 7 is cut away at the end farthest from the openings *a*, *b* and *c* to provide passage for products of combustion from compartments 8 and 9 to compartment 10 and into the throat 11 of the flue 12.

A vertical evaporating chamber 13, in order to be insulated against heat radiation, 60 is arranged within the flue 12 and is seated upon a support 14 which has a concave face 14' to receive the convex bottom 14^a of the evaporating chamber, and also has a passageway 31^a through which pipe 31 is arranged to withdraw residuum from the bot-

tom of the chamber 13. Channels 15 and 16 are arranged from the throat 11 through the lower portion of the support 14 and communicate with ports 17, 18, 19 and 20 which penetrate such support and permit the heat leaving the furnace to be carried into the flue and evenly distributed around the evaporating chamber.

As shown, I provide an insulating wall 21 which entirely surrounds the lower portion of the evaporating chamber. Such wall 21 may be of fire brick, asbestos or any other heat insulating material and may rise to any desired height around the evaporating chamber. Such wall 21, as shown, prevents the flame from the furnace coming into contact with the walls of the evaporating chamber. Such wall 21, as shown, prevents the flame from the furnace coming into contact with the walls of the evaporating chamber and thereby prevents any of the oil therein from being too highly heated. Such wall 21 may be continued upwardly around such evaporating chambers to any desired height, and in some instances it may be desirable to extend the same to entirely cover the entire evaporating chamber to act as a heat retainer to prevent radiation of heat, as when the chamber is located outside of the flue and the insulating effect of the flue is dispensed with.

Preferably, the oil is conducted from the last retort in the furnace to the top of the evaporating chamber 13 by means of a pipe 5 which is insulated against heat radiation by a covering of asbestos 22, the pipe 5 when thus insulated being carried upwardly from such retort outside of the flue 12 until it reaches the height of the top of the evaporating chamber whence it crosses over to the flue and through the side thereof to the center of the top 23 of the evaporating chamber through which it enters as at 24. I have shown in dotted lines in Fig. 2 how such pipe 5 may be run directly into the flue 12 at a point slightly above the level of the retorts and into the evaporating chamber and upwardly therein, the numeral 5, in dotted lines, indicating the pipe, and 22, in dotted lines, indicating the insulation surrounding the pipe outside of the flue. In this arrangement, as shown in dotted lines, the oil is delivered centrally within the evaporating chamber the same as shown by pipe 5 in solid lines.

A spreader 25 is arranged below the delivery point of the oil within the evaporating chamber, which spreads the same onto a perforated disk shaped baffle plate 26, through which it falls onto a like perforated baffle 27. In its passage through the perforations in the baffles 26 and 27, the oil is thoroughly broken and agitated which reduces the tension thereof upon the several series of oils which are expansible at the temperature ex-

isting in the oil. The agitated oil after passing through the last baffle 27 falls upon an imperforate spreading cone 28 which directs the liquid onto the wall 29 of the chamber 5 over which it flows to the bottom 30 of the evaporator where it is collected and withdrawn through a suitable pipe such as 31. Imperforate spreading cones 32, 33, 34 and 35 are provided along the chamber to redirect any oil back onto the wall in case through any cause it might fall away therefrom. The baffle plates 26, 27, and imperforate spreading cones 28, 32, 33, 34, and 35 which direct the oil upon the inner wall 29 of the chamber over which it flows downward, constitute, with said walls, means for retarding the flow of the oil whereby to permit the expanded molecules to fully vaporize while the oil is maintained in a divided condition. It will of course be understood however that other means for so retarding the oil during its flow through the vaporizing chamber may, if desired, be employed under my invention.

25 The spreader 25, baffle plates 26 and 27 and imperforate cones 28, 32, 33, 34 and 35 are shown as supported within the chamber by means of a perforated vapor collecting pipe 36 which is perforated beneath each of 30 the several cones as indicated at 37. Vapor outlets 38, 39 and 40 lead from the vapor collecting pipe 36 through the wall of the evaporating chamber and through the wall of the flue 12 and enter a vertical vapor 35 column 41 outside the flue. A vapor condensing line 42 connects with the vapor column 41 through which the vapors are drawn to a suitable condenser, such vapor line 42 being shown in Fig. 1 as broken in 40 order to contract the view. The vapor column 41 is supported upon a post 43 in order to relieve the strain upon vapor outlets 38, 39 and 40.

A vapor relief line 44 is provided to take 45 any vapor generated within the several retorts and is connected to each of the several retorts through the legs 45. Such vapor relief line connects with the oil pipe 5 into which all vapors generated within the several retorts are delivered and conveyed 50 thereby into the evaporating chamber. Valves 46 are provided in the several vapor legs 45 to regulate the passage of vapors from the several retorts to the vapor relief line.

55 A by-pass pipe 47 is provided through which oil may be passed from the retorts without passing through the pipe 5 into the evaporating chamber, valves 48 and 49 being arranged to be opened or closed as needed to direct the flow into the evaporating chamber or through the by-pass 47. It is to be understood that such by-pass 47 leads to some suitable receiving tank for 60 such oil. Such by-pass pipe is broken in the

accompanying drawings in order to contract the view.

Temperature telling means, such as a self recording thermometer 48, is arranged to indicate the temperature of the oil heated within the retorts as it enters pipe 5, while a like temperature indicating and recording means 49 is provided to indicate the interior temperature of the evaporating chamber. The tube from the indicating and recording means 49' is shown in Fig. 2 passing through a tube in the left side of the flue 12 and into the evaporating chamber 13. By this means I am able to observe the equality or inequality of the interior temperature of the evaporator and the oils being delivered thereto.

By locating the evaporating chamber within the flue I am enabled to insulate the chamber against heat radiation, as the heat from the furnace will generally, to all practical ends, be sufficient to maintain the temperature of the interior of the chamber, but to insure against any decrease of temperature therein, and to insure the maintenance of the buoyancy of the expanded oils, I provide an auxiliary interior heater for the chamber comprising a steam superheating coil 50 which is arranged within the influence of the heat in the furnace at 10 and which is connected by pipe 51 which enters the evaporating chamber and delivers steam to a perforated coil 52 in the bottom of the evaporating chamber. By means of such superheating coil 50 and coil 52 I am enabled to at any time introduce steam heated to the desired temperature to the interior of such evaporating chamber to maintain the temperature within the same at the required degree. As shown, such perforated coil 52 is located at a point within the evaporating chamber where it will be submerged in the oil at the bottom of the chamber, and when steam is delivered therefrom it will first pass into an oil body and thence rise throughout the entire body of the still, thereby maintaining everything within the chamber at the same temperature, as well as keeping all of the expanded oil vapors afloat until they have an opportunity to escape from the chamber.

110 The form of insulation surrounding the evaporating chamber may be varied and other forms of such insulation against heat radiation substituted, as for instance surrounding the entire chamber with the wall 21, in which case the temperature within the chamber would be maintained by the admission of the superheated steam, in which event the evaporating chamber might with safety be located exterior of the flue. In 115 practice, however, I have demonstrated that by placing the evaporating chamber within the insulating influence of the furnace flue, a considerable saving in fuel is obtained in the operation of the device on account of the 120 125 130

requirement of a less amount of superheated steam being required in maintaining the parity of temperature within the evaporating chamber.

5 I provide a vertical indicating column 55 outside of the flue which communicates with the bottom of the evaporating chamber, and below the oil body therein by means of leg 56, and with the evaporating chamber above such oil body by means of leg 57. Pet cocks 58 are arranged along the length of such indicating column whereby the attendant may determine the height of oil within the bottom of such evaporating chamber.

15 The method of operation of the particular embodiment of my invention disclosed herein is as follows: The oil in its crude state is admitted to the tubular retorts 3, in the furnace 1, and heat is applied by any suitable means, such as the use of a fuel oil, to the interior of the compartments 8, 9, and 10. The oil passes through these retorts in order, being admitted through the pipe 4 and being carried therefrom through the insulated pipe 5 to the top of the evaporating chamber. As previously explained the oil is raised to the temperature required for evaporation of the series desired in these retorts before being admitted to the evaporator. The oil entering the top of the evaporating chamber 13 first passes on to the spreader 25 from which it falls on to a perforated baffle 26 through which it falls to a like perforated baffle 27 which tends to further separate and distribute it. From this baffle plate 27 it falls on the spreading cone 28 and passes therefrom to the inner walls 29 of the evaporating chamber from which it passes downwardly in a finely divided state. Additional spreader cones 32, 33, 34, and 35 tend to return to the inside wall of the condensing chamber any oil which may become detached therefrom. The oil in its downward passage is maintained at practically its initial temperature by means of suitable insulation on the outer surface of the evaporating chamber and by the addition of sufficient heat to the interior of the evaporating chamber to supply whatever radiation losses may occur therein.

55 The vapors liberated from the oil on the inner wall 29 of the evaporating chamber 13 pass through the perforations 37 in the vapor collecting pipe 36, and are taken therefrom through the vapor outlets 38, 39, and 40 into the vapor column 41 outside the evaporating chamber. Heat may be applied to the evaporating chamber from the outside by the flue gases or by the introduction of steam to the perforated coil 52 in the bottom of the evaporating chamber. Various methods of maintaining the interior of this chamber at the critical temperature may of course be employed without departing from the spirit of my invention as hereinbefore

explained, for example: The evaporating chamber may be so heat insulated that it will not be necessary to apply external heat. The vapors from the vertical vapor column 41 are drawn off through the vapor condensing line 42 to suitable condensers not shown.

70 It is to be understood that it is desirable to provide a sufficient space within the evaporating chamber above the body of oil collected in the bottom thereof to accommodate the expanded vapors from the oil without pressure, and it is desirable to arrange the means for dividing the oil to relieve the tension thereof upon the expanded vapors in such a manner as to avoid entraining them with the descending oils, but I desire it to be understood that I consider my invention to broadly include any arrangement of an expanding or evaporating chamber, having 75 vapor outlet and residuum outlet means, which is arranged to receive a previously heated oil and is provided with means to prevent heat radiation or loss of heat from such chamber, and means for adding auxiliary heat thereto in order to maintain the expanded vapors in a buoyant condition, thereby preventing any contraction or condensation thereof while within the evaporating chamber.

80 In order to fully comprehend my invention it is necessary that the person desiring to practice the same should be informed as to the sensitive nature of petroleum oil vapors and their requisite treatment, and should understand the importance of maintaining the temperature of the expanded or volatilized oil within the chamber in which it is freed from the entanglement with the heavier oil in which it has heretofore existed, and also the importance of maintaining the vapor in a fully expanded condition until it is withdrawn to a condensing apparatus where it will contract to its normal condition, and in that connection I desire to 95 say that my invention is not to be confused with those in which attempts have been made to reduce all of the series of hydrocarbons existing in a natural oil to one series by heating the oils under pressure to a 100 very high temperature and then suddenly expanding such highly heated oils within an expanding chamber, for the reason that in such processes the molecular structure is broken in the lower series with the view of 105 combining them with the higher series. This attempt to so break up and recombine the several series of an oil is never accomplished except at the cost of generating methane or other light gas, with its attendant loss in volume of oil treated.

110 By the use of my invention a gentle action is had and all breaking of the molecules of oil is prevented. All of the oil taken from the original oil in vapor form 115

is a true whole oil, while the residuum remaining after the vapors are extracted is a whole oil showing no traces of free carbon, and as proof thereof the condensed vapors 5 may be mixed again with the residuum, if desired, and no evidence of distillation or treatment can be detected, thus showing that no breaking of the oils has resulted. This feature is especially valuable in such cases 10 as where an amount of water exists in combination with a petroleum oil and the same can only be removed by heat. By the use of my apparatus the oil can be heated to the degree necessary to vaporize the water 15 and thereby break its bond with the oil. The vapors of water and whatever vapors of oil are evolved are kept buoyant within the evaporating chamber until they are drawn into the condenser. When such 20 vapors of water and oil have been cooled down and condensed, the oil will rise to the top of the water and may be drawn off, after which it can be again mixed with the oil from which it has been extracted without 25 leaving any traces that the same has ever been treated.

I desire it to be understood that by the term "insulated against loss of heat by radiation" I mean to define the loss of temperature within the evaporating chamber through the heat of the vapors and oil within such chamber being absorbed by the surrounding atmosphere, in which event the vapors within the chamber would decrease 35 in temperature and contract accordingly, and that series which was at its critical temperature of vaporization would be influenced to condense. It is of the essence of my invention to at all times provide means 40 whereby all of the vapors liberated from the oil within the chamber are never subjected to a contracting temperature while within the evaporating chamber.

What I claim is:—

45 1. The process of distilling from petroleum an oil of a given vaporizing temperature which consists of raising the temperature of the petroleum to said vaporizing temperature, subsequently passing the petroleum 50 through a vaporizing chamber maintained at said vaporizing temperature throughout and introducing into the chamber a heated gaseous medium having a temperature greater than that of the petroleum when it 55 enters said chamber thereby maintaining the vapors in their expanded form, retarding the flow of the petroleum to maintain it in a divided condition during its passage through the chamber, permitting the vapors 60 to escape from said chamber, and then condensing the vapors.

2. The process of separating hydrocarbons having a vaporizing temperature below a certain value from a complex mixture of 65 hydrocarbons, which consists of raising the

temperature of the mixture while in liquid form to the vaporizing temperature of a predetermined series, then passing the mixture through a vaporizing chamber maintained at said vaporizing temperature throughout and while therein dividing the mixture and retarding its flow therethrough so as to maintain the mixture in a divided condition during its passage through said chamber, and introducing in said chamber 75 superheated steam at a temperature above that of the incoming mixture.

3. In an apparatus for distilling petroleum and preventing condensation of the vapors thereof within the evaporating chamber, the combination of oil heating means, an evaporating chamber having a vapor outlet and residuum outlet arranged adjacent to such oil heating means constructed to receive and finely divide the oil and to effect a retardation of the oil while passing therethrough, means for conveying the heated oil from the heating means and delivering the same to the interior of the evaporating chamber, insulating means around such evaporating chamber adapted and arranged to prevent loss of heat therefrom by radiation, and means for introducing a heated gaseous medium to the interior of such evaporating chamber, the temperature of the 95 evaporating chamber being maintained the same throughout as that of the incoming oil.

4. In an apparatus for distilling petroleum and preventing the condensation of the vapors thereof within the evaporating 100 chamber, the combination of a furnace, an oil heating coil arranged therein, an evaporating chamber arranged adjacent to such furnace provided with means to divide the oil and constructed and arranged to retard the flow of oil therethrough, insulating means arranged around such evaporating chamber to prevent heat radiation therefrom, means for introducing steam into the chamber at a temperature above that of the 110 incoming oil, means for conveying oil heated within the coil in the furnace to the top of the evaporating chamber, means for withdrawing vapors from the chamber, and means for withdrawing residuum from the 115 chamber, the temperature of the evaporating chamber being maintained the same throughout as that of the incoming oil.

5. In an apparatus for distilling petroleum and preventing the condensation of the vapors thereof within the evaporating chamber, the combination of a furnace, an oil heating coil arranged within the furnace, an evaporating chamber arranged adjacent to such oil heating coil and furnace, means for connecting the oil heating coil with the evaporating chamber to deliver the oil heated in the coil into the upper portion of the evaporating chamber, means within the evaporating chamber adapted to divide such 125

heated oil to reduce the tension thereof on the volatilizable vapors therein at the temperature of the oil and also to retard the flow of the oil through the chamber, insulating means arranged around such evaporating chamber to prevent radiation of heat therefrom, means for superheating steam, means for introducing such superheated steam to the interior of such evaporating chamber whereby the temperature of the vapors evolved within the chamber are maintained, vapor outlet means from the chamber, and residuum outlet means from the chamber, the temperature of the evaporating chamber being maintained the same throughout as that of the incoming oil. 15
